FIG. 2

FIG. 3

FIG. 1

FIG. 4

FIG. 1. -

FIG. 2. -

FIG. 3. -

FIG. 4. -

FIG. 5. -

FIG. 1 is a top plan view of an instrument case in the open position showing my new design;

FIG. 2 is a right side elevational view of FIG. 1, the left side elevational view being identical thereto and opposite hand;

FIG. 3 is a front elevational view of FIG. 2;

FIG. 4 is a rear elevational view of FIG. 2;

FIG. 5 is a top plan view of the instrument case in the closed position;

FIG. 6 is a right side elevational view of FIG. 5, the left side elevational view being identical thereto and opposite hand;

FIG. 7 is a front elevational view of FIG. 6;

FIG. 8 is a rear elevational view of FIG. 6; and

FIG. 9 is a bottom plan view of FIG. 6.

The dominant feature of the present design resides in the appearance of the instrument case exclusive of the

various forms of gauges, meters, switches, knobs and lights which may be installed therein.

I claim:

The ornamental design for an instrument case for a numerical training simulator or the like, substantially as shown and described.
